UNITED STATES PATENT OFFICE.

HENRY L. CARPENTER, OF MINNEAPOLIS, MINNESOTA.

GARTER.

1,069,852.

Specification of Letters Patent. Patented Aug. 12, 1913.

Application filed September 29, 1910. Serial No. 584,448.

To all whom it may concern:

Be it known that I, HENRY L. CARPENTER, of Minneapolis, Hennepin county, Minnesota, have invented certain new and useful Improvements in Garters, of which the following is a specification.

This invention relates to improvements in garters and particularly to improvements in garters designed for men's wear, and the objects of the invention are to provide a garter which can, at one operation, be made to draw up the stocking and at the same time, if desired, adjust the garter upon the leg of the wearer.

The invention consists generally in the constructions and combinations hereinafter described and particularly pointed out in the claims.

In the accompanying drawings forming part of this specification, Figure 1 is a perspective view of a garter embodying my invention, Fig. 2 is a sectional elevation showing the parts free and in position for adjustment, Fig. 3 is a similar view showing the parts locked against movement, Fig. 4 is a section on line $x-x$ of Fig. 3, Fig. 5 is a detail section of the clasp for engaging the sock, or stocking, Fig. 6 is a detail plan showing the means for engaging the cord with one of the pulleys.

In all of the drawings, 2 represents the body of the garter, which consists preferably of suitable elastic webbing.

3 represents a suitable clamp holder, preferably formed of sheet metal, and having at one end a loop 4, through which the web 2 passes. The end of this web is adjustably secured in position by means of a sliding clasp 5. Upon the other end of the web 2 is a flat loop 6. The webbing passes behind this and its end is then turned backward upon itself and passed back through the loop 6, and usually projecting beyond the end of the loop at 7. The object in passing the webbing back of the loop 6 is to prevent the metal loop from coming in contact with the leg.

The clamp holder 3 is provided with a pulley 8 and also with a locking device, such as a double pointed cam lever 9, having a handle 10. The handle 10 projects beyond the edge of the clamp-holder and is provided with a suitable finger piece 11, projecting over the outside surface of the clamp-holder. By means of this finger piece the cam can be adjusted. The loop 6

has pivotally supported upon it a pulley 20. This pulley is mounted upon a pin 12 that passes through a spring 13. The pin has one end journaled in said spring and its other end journaled in the loop 6. The spring 13 has a loose end 14, which bears against the body of the loop 6 and under which the cord 15 may be slipped for the purpose of engaging it with the pulley 20 after the garter has been put in place. The end of the cord 15 is provided with a suitable stocking or sock clasp 16, having a pivoted jaw 17 and a spring 18 that engages said jaw. The clasp employed, however, in this device may be of any suitable construction.

In operation, the garter is placed around the leg of the wearer and the loop of the cord 15 is carried under the end of the spring 13 into engagement with the pulley 20. The clasp 16 is engaged with the top of the sock or stocking and the operator then pulls the cord 15. This pulls up the stocking to the required position and at the same time tightens the garter upon the leg of the wearer. By gripping the cord in the holder 3 when the locking device is in its unlocked position, it is possible to tighten the garter around the leg or draw up on the stocking leg, without one tightening operation affecting the other. When brought to the proper position the lever 10 is turned by means of the finger piece 11 and the double pointed cam 9 is made to lock the cord 15, both at the top and bottom of the inner wall of the clamp-holder 3. By this means the sock or stocking is secured at the desired height and the garter itself is brought to the proper degree of tightness upon the leg of the wearer. The double pointed cam within the clamp-holder clamps the cord between itself and the inner surfaces of the clamp-holder, and this position the cord retains until it is desired to release the sock, or to remove the garter from its position on the leg of the wearer.

The details of the construction may be varied in many particulars without departing from my invention.

I claim as my invention:—

1. The combination, in a garter, with an elastic webbing forming the body of the garter, having at one end a clamp-holder and at the other a suitable pulley, of a cord passing through said clamp-holder and around said pulley and provided with a

stocking clasp and a double pointed cam mounted upon a pivot, adapted to be engaged with said cord for locking it in said clamp-holder, substantially as described.

5 2. The combination, with a band adapted to encircle the leg, of a clamp holder attached to one end of said band, a cord guide carried by the other end of said band, a cord having means for attachment to a 10 stocking and adapted to pass through said holder and said guide, and means for locking said cord in said holder.

15 3. A garter comprising a band, a holder at one end of said band, a cord guide at the other end of said band, a cord having a stocking clasp at one end and passing through said holder and around said guide, and means mounted in said holder for gripping the free end of said cord, said gripping

means allowing the movement of one end of 20 said cord to draw up the stocking leg or the movement of the other end of said cord to tighten the garter on the leg.

4. A garter comprising a band, a holder, and a cord guide, a cord adapted to slide in 25 said guide and said holder and having a stocking clasp, means carried by said holder for gripping the cord, said gripping means allowing the movement of one end of said cord to draw up the stocking leg, or the 30 movement of the other end of said cord to tighten the garter on the leg.

In witness whereof, I have hereunto set my hand this 22d day of September 1910.

HENRY L. CARPENTER.
